BY

Thomas Donnelly
ATTORNEY.

UNITED STATES PATENT OFFICE.

FRANK HOFFMAN, OF DETROIT, MICHIGAN.

PROPELLER.

Application filed July 14, 1927. Serial No. 205,573.

My invention relates to a new and useful improvement in a propeller adapted for use particularly on boats, and has for its object the provision of a propeller which may be utilized in conjunction with compressed air or steam for effecting a propelling of the boat through the water.

It is another object of the invention to reduce the friction of the boat resulting from the contact of the water therewith so as to economize on the consumption of power used for propelling the boat through the water.

Another object of the invention is the provision of a rotary propeller having passages formed therein through which fluid may be projected to impinge against the wall of water rising rearwardly of the boat and forwardly and at the sides of the boat so as to assist in propelling the boat through the water.

Other objects will appear hereinafter.

The invention consists in the combination and arrangement of parts hereinafter described and claimed.

The invention will be best understood by a reference to the accompanying drawings which form a part of this specification, and in which

Fig. 1 is a fragmentary side elevational view of a boat showing the invention applied.

Fig. 2 is a front elevational view of a propeller embodying the invention with a part broken away and a part shown in section.

Fig. 3 is a fragmentary sectional view taken on line 3—3 of Fig. 2.

Fig. 4 is a fragmentary view taken on line 4—4 of Fig. 3.

Fig. 5 is a view similar to Fig. 3 of a modified form of the invention.

As shown in the drawings the invention is adapted for use with a boat 9 adapted for being driven through the water and

provided with a rudder 10 operated in the usual manner. The propeller shaft 11 is projected rearwardly of the boat in the usual manner and mounted on the shaft 11 which is formed tubular is a propeller having the

propeller blades 12 which radiate outwardly from a hub 13 which is threaded or otherwise secured on the propeller shaft 11. These blades are formed hollow and communicate with the propeller shaft 11 so that

steam, compressed air or other suitable fluid

may be forced in the direction indicated by the arrows through the shaft 11 and into the propeller blades 12 from which it issues through the enlarged opening 14 formed in the blades so as to impinge against the wall 15 of water which is rearwardly of the boat and which is constantly moved rearwardly of the boat upon rotation of the propeller. This stream of fluid issuing from the propeller will assist the propeller in driving the boat forwardly. Projecting forwardly of the boat is a propeller shaft 11' upon which a similar sort of propeller is mounted, the opening in the propeller positioned at the forward part of the boat being directed toward the rear of the boat so as to cause the fluid forced therefrom to impinge against the wall 15' of water which is traveling rearwardly of the boat, thus forcing this water away from the sides of the boat and causing less resistance, while at the same time, urging the boat in a forward direction.

Formed on the outer wall of the propeller in registration with the shaft 11 is an outward projection 16 which provides a chamber 17, the compressed air, steam or other fluid, being forced through the shaft 11, striking in the chamber 17, and being thence deflected toward the openings 14 formed in the blades. As shown in the drawings these openings are flared outwardly so that a distribution of the fluid forced therefrom over a large area of the water wall is effected.

These openings also are inclined diagonally so that when the power ordinarily used to rotate the propeller shaft 11 is shut off and the fluid under pressure is emitted from the propeller blades, it will have a tendency to rotate the propeller blades in the opposite direction, or at least resist their continued

rotation, so that a retarding of the boat may be effected by the continued flow of the fluid from the propeller blades after the propelling power has been shut off.

In Fig. 5 I have shown the shaft 11 communicating with a chamber 17 formed on the propeller blade 12 having the opening 14 formed therein. The hub 13' being inclined to the blades of the propeller shaft, an inclined mounting of the propeller on the shaft 11 is effected.

In this way I have provided a means for assisting the propelling of the boat through the water, and provided also a means for checking the speed of the boat, when de-

sired. The use of the fluid for this purpose is believed to result in an economy in the propelling of the boat and to add to the efficiency generally of the operation of the 5 propelling mechanism.

While I have illustrated and described the preferred form of my invention, I do not wish to limit myself to the precise details of structure shown, but desire to avail myself 10 of such variations and modifications as come within the scope of the appended 15 claims.

Having thus described my invention what I claim as new and desire to secure by Letters Patent is:

1. In combination, a tubular propeller shaft, a propeller blade mounted on said shaft, the blades thereof being hollow and communicating with the interior of said 20 shaft, each of said blades having an enlarged outlet opening formed therein, said opening being flared outwardly, and a

chamber on said blade positioned opposite the end of said shaft, said chamber communicating with said shaft and with each 25 of said blades the body of said blades being inclined forwardly of said shaft.

2. In combination, a tubular propelling shaft; a tubular propeller mounted on said shaft and communicating therewith, the blades of said propeller being hollow and communicating with the interior of said shaft, each of said blades having an enlarged outlet opening formed therein, said opening being flared outwardly; a conical-shaped projection on the outer face of said propeller to provide at the central portion 30 of said propeller and opposite the end of said shaft a conical-shaped chamber communicating with said blades.

In testimony whereof I have signed the foregoing specification.

FRANK HOFFMAN.
